UNITED STATES PATENT OFFICE.

WILLIAM TOMS WALKER, OF ROANOKE, VIRGINIA, ASSIGNOR OF ONE-HALF TO J. A. WHEELER, OF ROANOKE, VIRGINIA.

RAIL-BENDER.

1,127,124.

Specification of Letters Patent.

Patented Feb. 2, 1915.

Application filed July 14, 1914. Serial No. 850,976.

To all whom it may concern:

Be it known that I, WILLIAM T. WALKER, a citizen of the United States, residing at Roanoke, in the county of Roanoke and State of Virginia, have invented a new and useful Rail-Bender, of which the following is a specification.

The invention relates to improvements in devices for bending rails.

10 The object of the present invention is to improve the construction of devices for bending rails and to provide a simple, practical, and efficient rail bending device of great strength and durability, adapted to be 15 conveniently carried and capable of readily bending a rail and of being readily operated to impart to the rail a continuous curve of the desired radius.

With these and other objects in view the 20 invention consists in the construction and novel combination of parts hereinafter fully described, illustrated in the accompanying drawings, and pointed out in the claims appended hereto, it being understood that 25 various changes in the form, proportion, size and minor details of construction, within the scope of the claims, may be resorted to without departing from the spirit or sacrificing any of the advantages of the in- 30 vention.

In the drawing:—Figure 1 is a plan view of a rail bender constructed in accordance with this invention, and shown applied to a rail. Fig. 2 is a transverse sectional view 35 on the line 2—2 of Fig. 1. Fig. 3 is a transverse sectional view on the line 3—3 of Fig. 1. Fig. 4 is transverse sectional view on the line 4—4 of Fig. 1. Fig. 5 is a horizontal sectional view taken substantially on the 40 line 5—5 of Fig. 4, the rail being omitted.

Like numerals of reference designate corresponding parts in all the figures of the drawing.

In the accompanying drawings, in which 45 is illustrated the preferred embodiment of the invention, the rail bender comprises in its construction a plate or body 1 provided at a point intermediate of its ends with an inward extension 2 adapted to rest upon the 50 head 3 of a rail 4 and having an integral hook shaped enlargement 5 arranged in a vertical plane and projecting from the upper and lower faces and the edge of the exten-

sion 2. The depending portion of the enlargement 5 is provided at the inner edge 55 with a recess 6, adapted to receive the inner side of the head 3 of the rail, whereby the hook shaped enlargement is enabled to engage beneath the head of the rail and slidably interlock the bending device with the 60 latter. The recess 6 of the hook shaped enlargement 5 is designed, in practice, to be sufficiently large to accommodate the heads of rails of various sizes. The extension 2, which is preferably tapered, as 65 shown, is located nearer one end of the body than the other, forming a relatively short arm or portion 7 and a relatively long arm or portion 8. The short arm or portion 7 is provided at its inner edge with an enlarged 70 abutment 9, projecting from the upper and lower faces of the plate or body 1 and having an inner vertical abutting face 10 adapted to fit against the head 3 of the rail 4 at the outer side thereof. The abutment is 75 provided at its inner vertical face with a projecting flange 11, arranged in flush relation with the lower face of the abutment and projecting beneath the head of the rail, as clearly illustrated in Fig. 2 of the drawing. The flange 11 is arranged to accommodate the heads of the larger rails when 80 the plate or body is placed in a horizontal position thereon, and it coöperates with the hook shaped enlargement in interlocking the 85 bending device with the rail, whereby the bending device, after being engaged with the head of a rail, is adapted to be moved along the same without being disconnected 90 therefrom to produce a continuous curving 90 of the rail, as hereinafter fully explained.

The longer arm or portion 8 of the plate or body extends outwardly from the rail, and its terminal portion 12, which is thickened to form an enlargement, is spaced 95 from the rail and is provided at the inner side with a vertical socket 13, opening inwardly toward the rail and also open at the top and bottom. The socket 13, which is approximately rectangular, has side and 100 inner walls, and the plate or body is provided at its lower face with depending vertical flanges 14, forming continuations of the side walls of the socket. The socket 13 receives a rectangular base 15 of a jack 16. 105 The base 15, which is preferably squared,

is arranged at the outer end of the jack, and the latter is provided at its inner end with a head 17 having a horizontal recess 18, designed to be of a size to receive the 5 head of the largest rail and interlocking the jack with the outer portion of the same. The jack is composed of two tubular telescopic members 19 and 20; the tubular section or member 19 is provided at its outer 10 end with the base 15, and is formed integral therewith, while the other tubular section or member 20 is formed integral with the head 17. The inner end of the tubular member 19 is equipped with a nut 21, which 15 is engaged by an interiorly arranged longitudinally disposed screw 22, carrying a bevel gear 23 and journaled in a suitable bearing 24 of the head 17. The bevel gear, which meshes with a bevel pinion 25, is 20 located within the head 17, and the latter is provided at the bearing 24 with anti-friction balls 26, receiving the bevel gear. The bevel pinion 25, which meshes with the 25 gear 23, is fixed to the inner end of an operating shaft 27, and the latter is journaled in a suitable bearing 28, extending from the outer side of the tubular section or member 20. The operating shaft 27 also carries a ratchet wheel 29, preferably in the 30 form of a spur gear and engaged by a pawl or dog 30 of an operating lever 31, adapted to be oscillated to produce a continuous rotation of the ratchet wheel. The pawl or dog is reversible to enable the 35 shaft 27 to be rotated in either direction. The base or outer end of the jack is detachably secured within the socket 13 of the plate or body by clamping screws 32, piercing the flanges 14 at opposite sides of 40 the socket and engaging the said head. Any other suitable means may, of course, be employed for securing the head of the jack within the socket of the plate or body, and in practice, a jack having operating 45 mechanism of any desired construction may, of course, be employed. After the device has been engaged with a rail, the jack is operated to bend the rail by forcing the same away from the arm or portion 8. By 50 advancing the device along the rail after each bending operation, the rail may be continuously curved the desired radius. The sliding interlocking of the bending device with the rail, by means of the hook 55 shaped engaging portion and the flanged abutment, greatly facilitates the curving of a rail, and enables the same to be rapidly effected. The plate or body is provided near its center with an opening 33, adapted 60 to be engaged by the jaws of an ordinary rail carrying tong, (not shown). By this construction, two men may readily carry the

bending device from one point or place to another.

What is claimed is:—

1. A rail bending device comprising a body provided at one end with an abutment for engaging the proximate side of a rail and having its other end arranged in spaced relation with the same, the last mentioned 70 end having a socket with three sides opening toward the rail and also open at the top and bottom, an intermediate extension formed integral with the body and of a length to extend across and rest upon the 75 head of a rail, said extension being provided with a terminal hook-shaped portion arranged to engage under the head of the rail, a jack interposed between the spaced end of the body and the rail and including 80 a head to engage the head of the rail, and a base located at the other end of the jack and fitted in said socket and adapted to be placed in and removed therefrom at the 85 top of the body.

2. A rail bending device including a plate or body having an integral rail engaging abutment at one end and provided at an intermediate point with an integral engaging portion of a length to extend across the 90 rail and shaped to engage the head thereof at the side opposite that engaged by the abutment, the other end of the plate or body being arranged in spaced relation with the rail and provided with a polygonal socket 95 opening toward the rail, a jack provided at one end with a polygonal base fitting the said socket, the other end of the jack having a rail engaging head, and clamping means mounted on the plate or body at the 100 said socket and detachably and rigidly securing the jack thereon.

3. A rail bending device including a plate or body provided at one end and at a point intermediate of its ends with spaced means 105 for engaging a rail at opposite sides thereof, the other end of the body being arranged in spaced relation with the rail and having a socket opening toward the rail and also open at the top, a rail engaging jack provided at one end with a base fitted in the 110 socket and adapted to be placed in and removed therefrom at the top of the plate or body, and clamping means mounted on the plate or body at the socket for detachably 115 securing the jack therein.

In testimony, that I claim the foregoing as my own, I have hereto affixed my signature in the presence of two witnesses.

WILLIAM TOMS WALKER.
